UNITED STATES PATENT OFFICE

HAROLD L. DE LISLE, OF CHICAGO, ILLINOIS

BINDER FOR DOWN-HANGING SHEETS

Application filed July 16, 1928. Serial No. 293,069.

These improvements relates to binders for down-hanging sheets, for example blue prints and the like. The chief object is to provide a strong, durable and simple device for holding the sheets safely and securely and whereby the sheets may be inserted and removed in an easy and expeditious way, and whereby also they may be protected against abrasion and other injury.

10 In the accompanying drawings Figure 1 shows my improved holder almost in full face view or slightly in perspective; Fig. 2 shows the device with the clamping member removed; Fig. 3 shows part of a supporting 15 rack with the binder on an enlarged scale held thereby; Fig. 4 is a section through the binder complete at the place 4—4 of Fig. 1; and Fig. 5 is a cross-sectional view at the 20 place of the line 5—5 of Fig. 2 featuring the spring.

In practice the device is made of sheet-metal. The back 10 has at its top a normally forwardly-and-downwardly directed flange or turned-over part forming a recess or pocket 25 extending from end to end of the back. The bottom edge portion of the back is turned upon itself at 12 for strength and finish.

Two bolts 13 are shown as being permanently held to the back. To this end a 30 metal strip 14 formed as shown is spot welded to the back at the place of each bolt, the piece 14 having a countersink 14^a pressed into it to accommodate the bolt head and the back has a fin or projection 15 (Fig. 4) 35 pressed into the kerf of the bolt head. Part of the bolt head is in section in Fig. 4. The bolt may not turn on its axis nor come away from the back.

A trough-like clamping member 16 extends almost from end to end of the back. Its upper edge portion projects beneath the extension 11. Its lower end portion is turned over at 16^a for strength and to provide a rounded clamping edge. The bolts project 45 through openings in the member 16 and the knurled and kerfed nuts 17 and 18 hold the member 16 tightly upon the material to be clamped.

Figs. 2 and 5 show a medially-arranged 50 substantially U-shaped leaf spring 17. It is

spot-welded to the back and its free end presses outward against the clamping member 16. When the nuts are retracted the clamping member automatically releases the material.

The sheets as 18 are inserted so as to come against the bolts acting as stops.

The bar 19 may be of wooden dowel material, which is light and of ample strength. It extends from end to end of the device and 60 is retained at its ends by stops 120 partly cut and bent outward from the back. It rests on the bolts. A protective cover or shield 20, which may be paper or fabric, hangs upon the rod 19 and encompasses the sheet material 65 18. The cover has holes 19^a (Fig. 2) at the bolts.

The rack 22 and vertical members 23 in Fig. 2 may be considered to be parts of a 70 sliding support or a permanent support as desired. The rack shows how many of these holders may be closely assembled. The binder is supported by integral ears or longitudinal extensions 24 of the back strongly made by folding metal of the back upon itself. The bottom edge of these ears 24 is rounded. The 75 ends of the flange 11 go under the folded metal at 24.

These binders may be of any desired 80 length, and there may be variations in construction, size, arrangement etc. The cross-sectional views are to the scale and size employed by me. On these cross-sections the back is two and five sixteenths inches from top to bottom.

The operator removes one of the binders 85 from the rack and lays it and the continued sheets upon a table. Retracting the nuts he can insert or remove sheets with little effort or loss of time. The cover 20 saves much wear 90 and tear of the sheet material.

I contemplate as being included herein all 95 such changes, variations and departures from what is thus specifically illustrated and described as fall within the scope of the appended claims.

I claim:

1. In a binder of the character described 100 normally horizontally disposed for holding down-hanging sheets, the combination of a

long and narrow back member, a long and narrow clamping member extending substantially from end to end of and overlying the back member, the back member having downwardly-and-forwardly extending means at 5 it its upper edge portion under which the clamping member loosely extends for rocking action relative to the back member and for ready removability of the clamping member from the back member, the back member and 10 the clamping member being formed to provide a substantially deep longitudinally-extending space between them for the accommodation of sheets, the lower edge portion of the clamping member being opposite the lower 15 edge portions of the back member, and means for forcing the clamping member toward the back member.

2. The combination of claim 1 hereof in which the back member is substantially flat 20 and the clamping member is bowed away from the back member substantially on an arc from top edge to bottom edge of the clamping member and forming a trough-like construction of the clamping member in cross view.

25 3. The combination of claim 1 hereof together with a substantially U-shaped leaf spring carried by the back member, extending upward along the back member to above the middle thereof in the up-and-down directions 30 and then downward into engagement with the clamping member for forcing the clamping member away from the back member.

4. The combination of claim 1 hereof together with means carried by the device for holding a protective cover adapted to overlie sheet material held by the binder.

35 5. The combination of claim 1 hereof together with a longitudinally-extending bar between the back member and the clamping member for holding a cover adapted to protect sheet material held by the binder.

40 6. The combination of claim 1 hereof in which the back member has an extension at each end adapted to be engaged by binder-supporting means.

45 7. The combination of claim 1 hereof in which there are transverse bolt means for forcing the clamping member toward the back member and a longitudinally extending bar resting on the bolt means and between said members for holding sheet-covering material.

50 8. A binder of the character described normally horizontally disposed for down-hanging sheets, comprising a long and narrow substantially flat back member of sheet metal having its lower edge portion turned upward against its body to provide a strong and rigid clamping seat and having its upper edge portion turned downwardly-and-forwardly to provide a retaining extension, a long and narrow clamping member bowed outward in directions away from the back member and having its upper edge portion 55 loosely under said extension for rocking

movements of the clamping member relative to the back member, the lower edge portion of the clamping member being turned upward to provide a strong clamping edge, bolt means carried by the back member and extending in a direction toward the clamping member, and nut means associated with said bolt means and with the clamping member for drawing the clamping member toward the back member.

70 9. The combination with a binder of the character described comprising a long and narrow back member and a long and narrow clamping member with bolt means for drawing the clamping member toward the back member to clamp sheets between adjacent edges thereof, of a protective cover and means other than the sheet-clamping means for holding the protective cover to the clamping means whereby the sheets may be removed without removing the cover.
